UNITED STATES PATENT OFFICE.

ALBERT G. McCALLEB, OF CHICAGO, ILLINOIS, ASSIGNOR TO PINES MANUFACTURING COMPANY, OF CHICAGO, ILLINOIS, A CORPORATION OF DELAWARE.

SHUTTER APPARATUS FOR ENGINE RADIATORS.

Application filed March 1, 1924. Serial No. 696,152.

To all whom it may concern:

Be it known that I, ALBERT G. McCALLEB, a citizen of the United States, and resident of Chicago, in the county of Cook and State 5 of Illinois, have invented a certain new and, useful Improvement in Shutter Apparatus for Engine Radiators, of which the following is a full, clear, concise, and exact description, reference being had to the accompanying drawing, forming a part of this 10 specification.

My invention relates to a shutter apparatus for engine radiators, and is concerned with the provision of such an apparatus in 15 which the shutters close when the engine stops, which open only when the engine is operating and has attained a predetermined desirable operating temperature, and which when opened remain open until the operation of the engine ceases.

The drawing diagrammatically illustrates the application of my invention to a water cooled engine of the kind commonly employed on automobiles.

25 In the drawing, reference numeral 1 indicates a multiple cylinder water jacketed internal combustion engine provided with the intake manifold 2, within which a partial vacuum exists whenever the engine is in operation. At 3 is illustrated a fragment of the core of a suitable radiator, which, in automobile practice, is usually located in front of the engine and constitutes the front wall of an enclosure for the power plant of 30 the vehicle. The radiator is, of course, connected through suitable conduits (not shown) with the water jackets of the engine, so that the cooling medium may circulate or be circulated through the water jackets 35 and the radiator in a well known manner.

At 4 I have illustrated a plurality of shutters which control the cooling capacity of the radiator; i. e., when the shutters are open the radiator has its maximum cooling capacity, and when the shutters are closed the radiator has its minimum cooling capacity. These shutters may form parts of a radiator shutter attachment such as are illustrated in the patent to Christian Nielsen, Jr., No. 50,117,938, dated April 11, 1916, or may be supported within the radiator shell to constitute a so-called "built-in" shutter apparatus. In the present disclosure, the shutters are mounted for movement around horizontal axes in a suitable frame indicated at 5.

The shutters have a common operating bar 6, the spring 7 tending to hold the shutters closed.

Fixed with respect to the shutter frame is a cylinder 8, within which operates a piston 9 provided with a piston rod 10 which, if desired, may be guided by a spider 11 at the open end of the cylinder. The outer end of the piston rod is pivoted to one end of a link 12 which at its opposite end is operably connected with a bell crank lever 13 which is conveniently pivoted to the frame 5. The bell crank lever in turn is connected through a link 14 with the shutter operating bar 6. Thus it will be seen that the spring 7 normally tends to move the piston 9 toward the spider 11.

At 15 is illustrated a conduit which affords a suction communication between the engine manifold 2 and the closed end of the cylinder 8. The diameter of the cylinder 8 and the strength of the spring 7 are such that when the engine is operating, the partial vacuum existing in the cylinder 8 is sufficient to hold the shutters open, notwithstanding the tendency of the spring 7 to close the same.

It will be noted that the link 12 is provided with a notch 16 which, when the shutters are closed, lies opposite a latch 17. The said latch is in the form of a short bar having one end pivoted to the frame 5 and its upper end attached to a member 18 which constitutes a follower for a collapsible and expandable thermo-wafer cell 19. A spring 20 associated with the follower 18 serves to move the latch 17 to its locking position when the thermo-wafer cell collapses.

The thermo-wafer cell may be of any well-known type and is filled with a compound, conveniently containing ether, which appreciably changes its volume under changes in temperature. As here illustrated, the thermo-wafer cell bears against a heat conducting plate 21 which is supported by the shutter frame 5 and which lies in snug heat conducting contact with the radiator core 3. The heat conducting plate is conveniently formed of aluminum. The thermo-wafer cell is conveniently located within a housing 22, formed of aluminum or other suitable material; this housing being fixed to the aforesaid heat conducting plate and providing a sliding bearing to the follower 18 to which I have previously alluded. In some 110

installations it will be desirable to provide the housing 22 with a jacket of heat insulating material. Such a jacket is illustrated at 23.

5 The operation of the mechanism is as follows: When the engine is idle and cold, the shutters are closed and are positively locked against opening by the latch 17 which engages in the notch 16 of the link 12. When 10 the engine commences to operate, the partial vacuum existing in the cylinder 8 tends to move the piston 9 to open the shutters, but such movement of the piston is prevented by the latch 17. The shutters remain locked 15 in their closed position until the engine temperature, as evidenced by the temperature of the cooling medium and the radiator core, is increased to a predetermined point, say, for instance, to a temperature between 160° 20 to 200° of Fahrenheit. When the predetermined temperature is attained, the latch 17 is disengaged from the notch 16 by expansion of the thermo-wafer cell 19. The shutters are thereupon moved to their open position 25 due to the influence of the engine suction upon the piston 9, the shutters remaining open until the engine ceases to operate. As soon as the engine stops, the shutters move to their closed position under the influence 30 of the spring 20, the latch 17 engaging in the notch 16 as soon as the temperature of the radiator core decreases to a predetermined extent.

It will thus be seen that in the herein 35 illustrated embodiment of my invention, the shutters are always closed when the engine is not operating, are locked against opening when the engine operates until the engine has attained a predetermined temperature, 40 and when once opened remain open until the operation of the engine ceases.

Having thus illustrated and described one embodiment of my invention, what I claim 45 is new and desire to secure by United States

Letters Patent is:

1. In combination with an internal combustion engine comprising a cooling system including a radiator, means controlling the cooling capacity of the radiator, means 50 tending to actuate the controlling means to increase the cooling capacity of the radiator when the engine operates, locking means effective to prevent such actuation, and means for rendering the locking means ineffective when the engine attains a predetermined temperature.

2. In combination with an internal combustion engine comprising a cooling system including a radiator, means controlling the 60 cooling capacity of the radiator, means normally tending to actuate the controlling means to decrease the cooling capacity of the radiator, a second actuating means capable of overpowering the first, said second 65 actuating means tending to actuate the con-

trolling means to increase the cooling capacity of the radiator when the engine is operating, locking means effective to prevent the second actuating means from overpowering the first until the engine, starting from rest, attains a predetermined temperature, and 70 thermostatic means for rendering the locking means ineffective when the engine attains such predetermined temperature.

3. In combination with an engine comprising 75 a cooling system including a radiator, shutters for controlling the cooling capacity of the radiator, means for locking the shutters closed when the engine is at rest and cold, means for unlocking the shutters when the engine attains a predetermined temperature, and means effective 80 when the engine is operating to open the shutters when the same are unlocked.

4. In combination with an engine comprising 85 a cooling system including a radiator, shutters for controlling the cooling capacity of said radiator, means for locking said shutters closed when the engine is at rest and cold, thermostatic means for unlocking the shutters when the engine attains a predetermined temperature, and means for utilizing the suction of the engine to open and hold the shutters open when the latter 90 have been unlocked by the thermostat.

5. In combination with an engine comprising 95 a cooling system including a radiator, shutters for controlling the cooling capacity of said radiator, spring means adapted to close the shutters when the engine is at rest, means effective when the engine is in operation to open said shutters when not locked in closed position, means effective when the engine is cold and at rest 100 to lock said shutters closed, and thermostatic 105 means for rendering the locking means ineffective when the engine attains a predetermined temperature.

6. In combination with an internal combustion engine comprising a cooling system 110 including a radiator, shutters for controlling the cooling capacity of the radiator, spring means normally tending to hold the shutters closed, means operable by the suction of the engine tending to open the shutters when the engine is in operation, means for locking the shutters closed, and thermostatic means for unlocking the shutters when the engine has 115 attained a predetermined temperature.

7. In combination with an internal combustion engine including a cooling system comprising a radiator, shutters for controlling the cooling capacity of the radiator, spring means tending to hold the shutters closed, means operable by the suction of the engine capable of overpowering said spring 120 means and tending to open the shutters when the engine is running, a positive lock holding the shutters in closed position when the engine is cold and at rest, and a thermostat 125 130

responsive to the temperature of the radiator adapted to render the lock ineffective when the engine has attained a sufficiently high operating temperature.

- 5 8. A shutter apparatus for an engine radiator comprising shutters for controlling the cooling capacity of the radiator, means locking the shutters closed when the engine is at rest and cold, thermostatic means for rendering the locking means ineffective when the engine reaches a predetermined temperature, and means adapted when the engine is running to open the unlocked shutters and hold them open until the operation of the
- 10 engine ceases.
- 15 9. In combination with an internal combustion engine comprising heat radiating

means, shutters for controlling the heat radiating capacity of the engine, means for locking the shutters closed when the engine is cold and at rest, fluid pressure operated means for opening the shutters when unlocked during operation of the engine, and thermostatic means adapted to unlock the shutters when the engine during operation 25 has attained a predetermined operating temperature.

In witness whereof, I hereunto subscribe my name this 27th day of February, 1924.

ALBERT G. McCaleb.
